CHARLES MAURICE, OF NEW YORK, N. Y.

Letters Patent No. 74,840, dated February 25, 1868; and dated February 13, 1868.

LITHOGRAPHIC PRESS.

The Schedule referred to in these Letters Patent and making part of the same.

TO ALL WHOM IT MAY CONCERN:

Be it known that I, CHARLES MAURICE, of the city, county, and State of New York, have invented a new and improved Lithographic and Autographic Press; and I do hereby declare that the following is a full, clear, and exact description thereof, which will enable others skilled in the art to make and use the same, reference being had to the accompanying drawings, forming part of this specification, in which—

Figure 1 represents a vertical longitudinal section of my improved press, the plane of section being indicated by the line $x x$, fig. 2.

Figure 2 is a plan or top view, partly in section, of the same.

Similar letters of reference indicate corresponding parts.

This invention relates to a lithographic or other printing-press, in which the stone or block is held in an adjustable frame, which can be expanded or contracted, so as to be adapted to stones of different width.

The pressure is applied by a roller, which is placed over the frame across the same, and which is made heavy by a weighted frame, which is suspended from it, and in which the roller turns. The stone or block, when ready for printing, is covered with the paper or material upon which the print is to be transferred, and then a canvas cover is folded over the latter. The roller is then gradually turned by means of a crank at its end, and is by this revolving motion fed along the stone or block, from one end of the frame to the other, thereby pressing with equal force upon every portion of the paper, and insuring an equal print.

The stone can be adjusted up and down, so as to come under the pressure of the roller. The weight of the frame which is suspended from the roller should be very heavy; still, it will be very easy to turn the roller and thereby press the paper on the stone. Two or three or more stones or blocks may be laid alongside of each other, in the same frame, so that they will all be operated upon by one roller. Thus, after the roller has passed over one stone, the paper is removed, and the stone reinked and new paper applied, while the roller passes over the other blocks or stones. Such a machine can, therefore, be kept, by the aid of two persons, in continuous motion, or, rather, continually working.

A represents a wooden or other metal frame, of suitable length and width, to support the adjustable casing for the stone. It is standing upon legs B B, which are sufficiently strong, and of the required length. C is the casing for the stone. It consists of upright side and end-pieces for surrounding the stone, and of a solid bottom, or of simple cross-pieces, in place of the latter, for securing it upon the frame A. To make the casing C laterally adjustable for stones or blocks of various widths, it has been made of two pieces, as if it were cut along its longitudinal axis. The bottom pieces are slotted, and are fastened by screws $a a$ to the frame A. It is easily understood that the lateral adjustment can be performed with facility and quickness. D is a roller, which is laid across the casing C, and from the ends of which a heavily-weighted frame, E, is suspended, the weights F on the latter being very heavy, so that the roller D will be steadied in its motions. The stone or block G, from which the impression is to be taken, rests upon a loose frame, or upon bars H H, and can be raised or lowered by means of screws $b b$, so as to be brought under the pressure of the roller D, as shown. The latter is provided with a crank, e, at one or each end, as shown. A frame, I, which is pivoted near to the end of the frame C, holds the canvas, paper, or cloth cover, which is let down upon the paper while the roller passes over the same. One such frame can be arranged at each end of the frame C, or one for each stone, of which any desired number can be used, one being laid alongside the other.

The operation and mode of working will be fully understood from the foregoing. The velocity of the passage of the roller from end to end of the stone can be varied by varying its diameter.

Having thus described my invention, what I claim as new, and desire to secure by Letters Patent, is—

1. The case C, when arranged so that it can be adjusted for wider or narrower stones or blocks, substantially as herein shown and described.
2. The case C, when consisting of two pieces or halves, which are laterally adjustable on the frame A, and when combined with the up-and-down adjustable frame or plates H, all arranged and operating substantially as herein shown and described.
3. The roller D, when connected with the weighted frame E, and with the stone or block G, so that by rotary motions of the roller, the latter will be moved over the stone, i. e., it will come in contact with and press upon each part of the paper and stone, and will not be drawn over the same, thereby insuring neatness of workmanship.
4. The adjustable frames C and H, in combination with the roller D and weighted frame E, all made and operating substantially as and for the purpose herein shown and described.

C. MAURICE.
